US0D1071424S

(12) **United States Design Patent** (10) **Patent No.:** **US D1,071,424 S**
(45) **Date of Patent:** **** Apr. 15, 2025**

(54) **LINT CATCHER**

(71) Applicant: **ADR Products, LLC**, Laramie, WY (US)

(72) Inventors: **David George Gregory**, Laramie, WY (US); **Adrienne Francesca Szabady**, Laramie, WY (US)

(73) Assignee: **ADR Products, LLC**, Avon, OH (US)

(**) Term: **15 Years**

(21) Appl. No.: **29/820,914**

(22) Filed: **Dec. 24, 2021**

Related U.S. Application Data

(63) Continuation of application No. 29/723,904, filed on Feb. 11, 2020, now Pat. No. Des. 940,979, which is a continuation of application No. 16/284,580, filed on Feb. 25, 2019, now Pat. No. 10,982,378, which is a continuation of application No. 15/453,652, filed on Mar. 8, 2017, now Pat. No. 10,214,851, which is a continuation of application No. 14/194,604, filed on Feb. 28, 2014, now Pat. No. 9,593,441.

(57) **CLAIM**

The ornamental design for a lint catcher as shown and described.

DESCRIPTION

FIG. 1 is a perspective view of a lint catcher, embodying our new design;

FIG. 2 is a first end elevation view thereof;

FIG. 3 is a second end elevation view thereof;

FIG. 4 is a first side elevation view thereof;

FIG. 5 is a second side elevation view thereof;

FIG. 6 is top plan view thereof; and,

FIG. 7 is a bottom plan view thereof.

The broken lines shown in the drawings illustrate portions of the lint catcher that form no part the claimed design.

1 Claim, 6 Drawing Sheets
